UNITED STATES PATENT OFFICE.

IRA H. FREESE, OF CLARKSBURG, WEST VIRGINIA, ASSIGNOR TO HAZEL-ATLAS GLASS COMPANY, OF WHEELING, WEST VIRGINIA, A CORPORATION OF WEST VIRGINIA.

APPARATUS FOR ANNEALING GLASSWARE.

Application filed January 17, 1921. Serial No. 437,657.

To all whom it may concern:

Be it known that I, IRA H. FREESE, a citizen of the United States, residing at Clarksburg, Harrison County, West Virginia, have 5 invented new and useful Improvements in Apparatus for Annealing Glassware, of which the following is a specification, reference being had to the accompanying drawings, in which—

10 Fig. 1 is an elevation of apparatus embodying my invention; Fig. 1^a is a diagram of the electrical generator connections for the apparatus; Fig. 2 is a plan of my improved apparatus; Fig. 3 is a section on lines 15 III—III of Fig. 2; Fig. 4 is a plan of one of the containers, partly broken away to show a series resistance; Fig. 5 shows a detail of the receptacles for the individual articles of glassware; and Fig. 6 shows a modified form of wiring for a container.

15 My invention relates to the annealing of glassware and comprises providing a plurality of containers for the ware, in which the temperature may be carefully regulated. As 20 I prefer to mount the containers on an endless belt and my improved apparatus is of the portable type and can be moved about as desired, this is a great advantage as compared to the ordinary masonry annealing furnace. 25 My invention also consists in the various features which I shall hereinafter describe and claim.

30 Referring to the drawings, 2 indicates the frame of the machine, which is supported 35 upon the wheels 3, so that it may be conveniently moved about a factory by any suitable source of power, such, for instance, as the motor 6^a. At each end of the frame 2 is a pair of sprockets 4, upon which is 40 mounted the endless belt 5. The sprockets 4 are driven by the motor 6. Secured to the belt 5 are the containers 7, each of which has therein a plurality of receptacles 8 for the individual articles of ware. Attached 45 to the outer ends of the pins 7^a, by which the containers 7 are secured to the belts 5, are the rollers 9, which move along and are supported by the channels 10 secured to the frame 2.

50 Each container 7 preferably has a series 55 resistance 11 therein, by which the receptacles 8 depending into each container 7 are heated, the bottom 12 of each receptacle being perforated, as is shown in Figs. 4 and 5, to permit the easy access of heat into the in-

terior of the receptacle. Electricity is supplied to the resistance through the roller contacts 13, which engage the pairs of bars 14^a, 14^b, 14^c. Each pair of bars 14^a, 14^b, or 14^c is separated from the other pairs of bars 60 and is connected with its respective generator A, B, or C., which provide successively lessening voltages and accordingly lessening degrees of heat as the containers travel 65 away from the loading point D. Each receptacle is provided with a lid 15, which is opened at the unloading station E and remains open as the container passes up-side down under the machine by reason of the flat surface 16 at the rear edge of the lid 70 15, which engages a corresponding flat surface on the container. When the receptacle reaches the loading station D the operator fills the receptacle and closes the lid, and the receptacle then proceeds to the unloading 75 station, thus completing the cycle.

In operation the machine is placed conveniently near a forming machine and the operator places the ware, which is still hot from the forming operation, in the receptacles 8 in the container 7 at the loading station D indicated at the left-hand side of Fig. 1. The lids 15 are then shut down and the forward movement of the container brings its 80 roller contact 13 into engagement with the bars 14^a, to which current is supplied by the generator A. I have found that a 500 volt generator supplies a suitable amount of heat. This generates a comparatively high 85 heat in the container, which should be approximately that at which the ware was when inserted in a receptacle; to wit, slightly above 900° F. The container moves along with the ware at this comparatively 90 high heat until the end of the bars 14^a is 95 reached and contact is made with the bars 14^b, which are connected with a generator (such as a 220 volt generator), which supplies a lesser degree of heat. Then, if desired, a third series of bars 14^c, connected 100 with a third generator C producing a lesser degree of heat, may be brought into use. Obviously, the number of changes in the annealing temperature and the duration of 105 any one temperature will depend on the ware being annealed. When the container arrives at the unloading station E at the right hand of Fig. 1, the receptacles are emptied and are returned by the endless belt beneath the machine to the loading point D, 110

In Fig. 6 I have shown a modification of my invention, in which the series winding 11^a passes around each receptacle in succession, thereby effecting an even distribution of the heat through the sides of the receptacles.

The containers preferably are made of sheet metal with a heat resisting sheathing 17, such as asbestos or the like, and the receptacles within the container must also be made of some material not affected by heat.

The terms and expressions which I have employed are used as terms of description and not of limitation, and I have no intention, in the use of such terms and expressions, of excluding any equivalents of the features shown and described, or portions thereof, but recognize that various modifications are possible within the scope of the invention claimed.

What I claim is:

1. In apparatus for annealing glassware which comprises a plurality of closed vessels, each having a plurality of receptacles 25 therein for the reception of articles of glassware, a heating element in each said vessel, and means for moving the vessels from a loading station to an unloading station and means for regulating the application of heat 30 therein.

2. In apparatus for annealing glassware which comprises a plurality of closed vessels, each having a plurality of receptacles therein for the reception of articles of glassware,

means for moving the vessels in a definite 35 cycle, and a heating element in each said vessel arranged to generate heat in and about the receptacles therein.

3. In apparatus for annealing glassware which comprises a plurality of closed vessels 40 having a plurality of receptacles therein for the reception of articles of glassware, an electric heating element in each vessel, means for supplying electrical energy to said elements, a closed cycle through which said 45 vessels operate, and means for regulating the wattage supplied to said elements during different portions of said cycle.

4. In apparatus for annealing glassware which comprises a plurality of closed vessels 50 having a plurality of receptacles therein for the reception of articles of glassware, an electric heating element in each vessel, a series of separated contacts for supplying current to such vessels at successively varying 55 voltages, and means for moving the vessels successively into engagement with said contacts.

5. In apparatus for annealing glassware which comprises a plurality of vessels mounted 60 for movement in a closed cycle, individual receptacles for glassware in each of said vessels, each receptacle being separated from the other receptacles in the vessel by a clear air space around the sides and bottom thereof, and a heating element in each vessel. 65

IRVING H. FREESE.
